UNITED STATES PATENT OFFICE.

GUSTAV EGLOFF AND HARRY P. BENNER, OF INDEPENDENCE, KANSAS, ASSIGNEES
TO UNIVERSAL OIL PRODUCTS COMPANY, OF CHICAGO, ILLINOIS, A CORPORATION
OF SOUTH DAKOTA.

APPARATUS FOR CRACKING OIL.

Application filed February 11, 1921. Serial No. 444,235.

This invention relates to improvements in apparatus for cracking oil and refers more particularly to that type of apparatus in which the oil is heated in a closed coil and delivered, preferably in liquid phase, to an expansion chamber where vaporization takes place. The novelty of the present invention consists in the means and manner in which the oil is introduced to the expansion chamber.

The object of the invention is to introduce this oil in separated streams or in finely divided condition at a high velocity against an impact member located in the expansion chamber. A velocity swirling effect is given to the liquid as it passes from the transfer line to the expansion chamber, thus bringing about a more rapid rate of cracking as the swirling heated liquid impinges under pressure against the baffle or impact member located in the expansion chamber.

By means of this apparatus, 35% of Healdton, Oklahoma fuel oil of 27 degrees Baumé, may be converted into 58 gravity gasoline, the oil being treated under a pressure of 200 pounds throughout the system and the temperature of the liquid at the transfer line being say, 895 degrees F.

In the drawings:

Fig. 1 is a view, partly in vertical section and partly in side elevation, of a cracking apparatus equipped with our invention.

Fig. 2 is an enlarged cross sectional view of one of the rifling nozzles.

Referring in detail to the drawings, 1 designates a furnace having burner 2, stack 3 and combustion chamber 4. In the combustion box is mounted the heating coil 5, which may take the form of continuous lengths of 4 or 5" pipe. The inlet side of the coil is connected by inlet 6 to charging pump 7. The discharge side of the coil is connected by insulated transfer line 8 to the elongated shell-like expansion chamber 9.

This expansion chamber 9 is provided with manhole plate 10, residue drawoff pipe 11 and vapor outlet pipe 12. The latter extends into dephlegmator 13, and is provided with a spaced cap member 14. The dephlegmator has baffles 15, reflux return line 16, leading to the feed line 6, and vapor outlet pipe 17 leading to the condenser 18. The condenser 18 is connected to a receiver 19, which receiver has pressure gauge 20, liquid level gauge 21, gas outlet pipe 22 and distillate drawoff pipe 23. Various parts of the system are provided with throttle valves 24, whereby a uniform or differential pressure may be maintained on all or part of the system as desired.

Referring now more particularly to the novel feature of the invention, the discharge end of the transfer line 8 is equipped with the delivery nozzle designated as a whole 25. This nozzle comprises an enlarged head portion 26 and a plurality of horizontally disposed tapering nozzles 27. The interior of each nozzle 27 is rifled as shown at 28 so as to cause a swirling action of the oil as it passes through the nozzle members proper. The arrangement is such as to cause a more or less violent swirling action and high velocity of the oil as it enters the expansion chamber. Directly in front of the nozzle is mounted an impact or baffle member 29, which may take the form of a segmental plate fitting closely around the internal wall of the upper part of the shell member 9. The arrangement is such as to throw the swirling oil under high velocity directly against the impact member 29 and thus tend to facilitate the speed and extent of reaction. The vapors pass out of the expansion chamber through the dephlegmator where the heavier portions are condensed and returned to the system for further treatment.

We claim as our invention:

A transfer line for a tube and drum oil cracking apparatus, adapted to convey heated hydrocarbon oil constituents from the tube into the drum, said transfer line terminating at its discharge end in a plurality of internally rifled nozzles, whereby the hydrocarbon oil constituents passing through said transfer line are subdivided and discharged therefrom at a high velocity in a plurality of circulatory paths.
